(57) **CLAIM**

The ornamental design for a screened enclosure water passageway, as shown and described.

DESCRIPTION

FIG. 1 is a front elevational view of the design.

FIG. 2 is a rear elevational view thereof;

FIG. 3 is a right side elevational view thereof, with the passageway in an open position, showing the position lock deployed;

FIG. 4 is a left side elevational view thereof, with the passageway in a closed position, showing the position lock in the stored position;

FIG. 5 is a top plan view thereof; and,

FIG. 6 is a bottom plan view thereof.

The broken lines are for illustrative purposes only and form no part of the claimed design.
